(57) **CLAIM**

The ornamental design for a bin body for weatherproof storage tote as shown and described.

DESCRIPTION

FIG. 1 is a top perspective view of a bin body for weatherproof storage tote;

FIG. 2 is a bottom perspective view thereof;

FIG. 3 is a top plan view thereof;

FIG. 4 is a right side elevational view thereof;

FIG. 5 is a front elevational view thereof; and,

FIG. 6 is a bottom plan view thereof.

A left side elevational view is not shown because it is a mirror image of the right side elevational view. A rear side elevational view is not shown because it is a mirror image of the front side elevational view. The dash-dot broken lines depict portions of the bin body for weatherproof storage tote and form no part of the claimed design.
